(57) **CLAIM**

The ornamental design for a folding knife as shown and described.

DESCRIPTION

FIG. 1 is a top perspective view of a folding knife.
FIG. 2 is a bottom perspective view of the folding knife illustrated in FIG. 1.

FIG. 3 is a top plan view of the folding knife illustrated in FIG. 1.

FIG. 4 is a bottom plan view of the folding knife illustrated in FIG. 1.

FIG. 5 is a rear view of the folding knife illustrated in FIG. 1.

FIG. 6 is a front view of the folding knife illustrated in FIG. 1.

FIG. 7 is a right side view of the folding knife illustrated in FIG. 1; and,

FIG. 8 is a left side view of the folding knife illustrated in FIG. 1.

The broken and phantom lines in the Figures illustrate unclaimed parts of the folding knife and form no part of the claimed design.
